SUPPORT FOR CURTAIN CRANES

Irwin W. Lemle, Chicago, Ill.

Application September 28, 1940, Serial No. 358,773

5 Claims. (CL 248—265)

The apparatus relates to supports for curtain cranes of the type in which the crane is adjustable to bring and maintain it into truly horizontal position.

One object of the invention is to provide a support of this type which is simple in construction and can be easily applied to a wall or frame.

Another object of the invention is to provide a curtain crane support which comprises a bracket section with a socket for the pivot shank of the crane and a hole for an attaching screw, a separate plate section with a hole for a screw for attaching it to a wall or frame, an outwardly projecting screw fixed to one of the sections and extending through a slot in the other, and a nut for clamping the members together and whereby quick and easy adjustment of the bracket section can be made to position the crane so it will be, and be efficiently secured in a, truly horizontal, position.

Other objects of the invention will be apparent from the following detailed description.

The invention consists in the several novel features which are hereinafter set forth and are more particularly defined by claims at the conclusion hereof.

In the drawing: Fig. 1 is a front elevation of a crane support embodying the invention. Fig. 2 is a section taken on line 2—2 of Fig. 1, the socket for carrying the crane being shown in elevation. Fig. 3 is a section on line 3—3 of Fig. 2. Fig. 4 is a perspective of the bracket member of the support. Fig. 5 is a perspective of the plate-member of the support.

The invention is exemplified in connection with a crane 10 on which a curtain 11 is suspended in any suitable manner, as well understood in the art. The crane is pivotally supported to swing horizontally, for example, by a vertical pivot stud or pintle 12 on the crane and a vertical socket 13 in which the pintle is journaled so that the crane may be swung into position parallel with the wall or at right angles thereto.

The improved support which exemplifies the invention comprises a bracket-member 14 and a separately formed plate-member 15. Member 14 comprises a flange 16, the back face of which is parallel to the wall or frame *a* on which the support is to be mounted and an integral channeled forwardly projecting arm 17 in which an arm 18 on the socket 13 is adjustably secured for adjusting the socket and crane-pivot to and from flange 16 by a screw 19 which extends through a slot 20 in arm 18 and is threaded to arm 17. The upper portion of flange 16 is adapt-

ed to fit against the wall or frame *a* and provided at its upper end with a hole 21 for a screw 22 whereby the bracket-member 14 and flange 16 can be attached to the wall or frame. The screw 22 permits flange 16 to swing in a plane parallel to the wall or frame sufficiently to permit the crane carried by bracket-member 14 to be angularly adjusted in a plane parallel to the wall or frame for the purpose of supporting the crane in a truly horizontal position. The back face of plate-member 15 is adapted to fit against a wall or frame *a* and is provided with prongs 15a for entering the wall or frame, which are usually formed of wood, and lock said member against angular displacement in a plane parallel to the wall or frame. The lower portion of plate-member 15 is provided with a hole 24 for a screw 23 which is adapted to attach member 15 to and force it against the frame. The prongs insure the holding of this member against rotational displacement by a single screw. A screw 25 projects transversely and forwardly from the outer face of plate-member 15 and is riveted thereto so that the screw will be secured against rotation in said member. Flange 16 has its lower portion 16a offset from the wall or frame and said portion is adapted to overlap the upper portion of member 15 which lies above the screw 23. Flange-portion 16a is provided with an arcuate slot 26 through which screw 25 extends. A cap-nut 27 is provided with a threaded socket in its inner end for engaging the thread of screw 25 and is adapted to clamp the inner face of the lower portion 16a of flange 16 against the front face of the upper portion of plate-member 15. The back face of portion 16a of flange 16 is knurled, as at 28, and the contiguous portion of the front face of plate-member 15 is knurled, as at 29, so that the contiguous faces of flange 16 and member 15 will interfit when cap-nut 27 is tightened to clamp said flange against the plate-member. A split spring lock washer 30 is interposed between the front face of flange portion 16a and the inner end of cap-nut 27 for exerting spring pressure from the cap-nut to hold flange 16 and plate-member 15 in interfitting relation and also to lock the nut against reverse rotation. The outer end of cap-nut 27 is provided with a kerf 31 so that it can be readily turned by a screwdriver.

In installing the support, the bracket-member and the plate-member are first assembled and connected together by the screw 25 and nut 27. Screw 22 will then be driven into the frame to attach the bracket-member 14 to and clamp

flange 16 against the front face of the frame *a*. Screw 25 will then be driven into the frame to lock plate-member 15 thereto, the prongs 23 entering the frame so that plate-member 15 will be locked against rotation on screw 25. If the crane 10 is not horizontal or if, after its initial installation, it should become displaced, it is only necessary to loosen cap-nut 27 and swing flange 16 and bracket-member 14 slightly on screw 22 until the crane is truly horizontal. The flange 16 is sufficiently flexible transversely to permit the knurled face to slide over the knurled face of member 15, for this purpose, if the screw 22 is tight. When the cap-nut 27 is again tightened the bracket-member 14 will be rigidly secured against displacement. Screw 25 is disposed below the lower end of flange 15 so that it will be accessible and can be driven into frame *a* while the plate and bracket members are assembled prior to installation on the wall or frame. The plate-member is rigidly locked to the frame against rotation by the prongs 23. The cap-nut, being located at the front of flange 16, is readily accessible for adjustment. In the event either of the screws 22, 25 becomes slightly loose in the frame, they will still function as pegs and the rigid connection between bracket-member 14 and plate-member 15 will prevent displacement of the support in a plane parallel to the wall or frame.

The invention exemplifies a curtain crane support which is simple in construction, can be produced at a low cost, can be easily installed while the components of the support are assembled as a unit, and can be readily adjusted from the front side of the wall.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A curtain crane support comprising the combination of a bracket-member provided with means for pivotally supporting the crane and with a hole at its upper end for pivotally attaching the bracket-member to a wall or frame, a plate-member adapted to fit against the wall or frame, means for fixedly attaching the plate-member to the wall or frame independently of the bracket-member, said members being provided with overlapping portions, the bracket-member having a slot therein, and means comprising a screw-threaded stud fixed to the plate-member and extending through the slot and a nut on the front end of the stud for adjustably clamping the overlapping portion of the bracket-member to the plate-member in different angular positions for securing the bracket-member against pivotal movement on its attaching means, said clamping means being adjustable while the plate-member is fixedly secured to the wall or frame.

2. A curtain crane support comprising the combination of a bracket member, means on said bracket member for pivotally supporting a crane, said bracket member being provided with a hole at its upper end for means for pivotally attaching it to a wall or frame and with a lower end portion having faces substantially parallel with the front of the wall or frame and below the crane supporting means, a plate member provided with faces substantially parallel to the

front of the wall or frame, means for fixedly securing the plate member to the wall or frame, the faces of the plate member and the lower end portion of the bracket which are substantially parallel to the front of the wall or frame having portions which overlap and fit together, and means for adjustably and fixedly clamping together the overlapped face portions while the plate member remains fixed on the wall or frame.

3. A curtain crane support comprising the combination of a bracket member, means on said bracket member for pivotally supporting a crane, said bracket member being provided with a hole at its upper end for means for pivotally attaching it to a wall or frame and with a lower end portion having faces substantially parallel with the front of the wall or frame and below the crane supporting means, a plate member provided with faces substantially parallel to the front of the wall or frame, the back face of the plate member being adapted to fit against the wall or frame, means for fixedly securing the plate member with its back face against the wall or frame, the front face of the plate member and the rear face of the lower end portion of the bracket which are substantially parallel to the front of the wall or frame having portions which overlap and fit together, and means for adjustably and fixedly clamping together the overlapped faces while the plate member remains fixed on the wall or frame.

4. A curtain crane support comprising the combination of a bracket member, means on said bracket member for pivotally supporting a crane, said bracket member being provided with a hole at its upper end for means for pivotally attaching it to a wall or frame and with a lower end portion having faces substantially parallel with the front of the wall or frame and below the crane supporting means, a plate member provided with faces substantially parallel to the front of the wall or frame, means for fixedly securing the plate member to the wall or frame, the faces of the plate member and the lower end portion of the bracket which are substantially parallel to the front of the wall or frame having interfitting and overlapped portions, and a screw for adjustably and fixedly clamping together the interfitting faces while the plate member remains fixed on the wall or frame.

5. A curtain crane support comprising the combination of a bracket member, means on said bracket member for pivotally supporting a crane, said bracket member being provided with a hole at its upper end for means for pivotally attaching it to a wall or frame and with a lower end portion having faces substantially parallel with the front of the wall or frame and below the crane supporting means, a plate member provided with faces substantially parallel to the front of the wall or frame, a screw below the lower end of the bracket member for fixedly securing the plate member to the wall or bracket, the faces of the plate member and the lower end portion of the bracket member which are parallel to the front of the wall or frame having portions which overlap and fit together, the lower end portion of the bracket member having a slot therein and a screw secured in the plate member and extending through said slot for adjustably and fixedly clamping together the overlapped face portions while the plate member remains fixed on the wall or frame.
